Original application February 6, 1940, Serial No. 317,604. Divided and this application September 15, 1941, Serial No. 410,960

6 Claims. (Cl. 164—50)

Our invention relates to means for forming notches in the longitudinal edge or edges of a strip.

An important object of the invention is to provide means of the above-mentioned character having a stationary part or parts to engage with the edge or edges of the strip, to guide the same during its longitudinal travel so that the strip will be properly centered with respect to the notching punch or punches.

A further object of the invention is to provide means of the above-mentioned character having an element to accurately guide the notching punch before it enters the notching die.

A further object of the invention is to provide a notching punch so constructed that the notching of the strip occurs after the notching punch enters the notching die.

A further object of the invention is to provide means whereby a discharge passage is provided in the notching die for the passage of the blanks cut from the strip.

Other objects and advantages of the invention will be apparent during the course of the following description.

The present application is a division of our application for Apparatus for producing eyelets, filed February 6, 1940, Serial No. 317,604.

In the accompanying drawing forming a part of this application and in which like numerals are employed to designate like parts throughout the same,

Figure 1 is a central vertical transverse section through notching apparatus embodying our invention, the notching punches being raised, and Figure 2 is a side view of the notching punches.

Figure 2 is a similar view, the notching punches being lowered.

Figure 3 is a horizontal section taken on line 3-3 of Figure 2.

Figure 4 is a similar view taken on line 4 of Figure 2.

Figure 5 is a similar view taken on line 5-5 of Figure 2, and,

Figure 6 is a perspective view of one of the notching punches.

In the drawing, wherein for the purpose of illustration is shown a preferred embodiment of our invention, means are provided to form notches or cuts 55, Figure 3, upon an elongated strip or ribbon 56, from which eyelets or the like are to be formed. This strip ordinarily has a thickness of .005 of an inch although the same may vary. The strip 56 is formed of any suitable metal, which can be drawn, such as nickel, copper, steel, brass, zinc, or the like. The strip

or ribbon 56 is fed longitudinally in a step-by-step manner, in the direction of the arrow and the notches are formed in succession in transverse pairs. The notches are circularly curved and are equidistantly spaced and the strip is fed each step for a length equal to the distance between the centers of adjacent notches.

The means which forms the notches 55 comprises a pair of notching punches 51, which are in transverse alignment, and spaced, and rigidly held within openings 58, formed in an upper shoe 48. The notching punches are cylindrical and tubular and have cylindrical bores 59. The notching punches 51 have straight horizontal cutting edges 60 and generally semi-cylindrical depending extensions 61, having inner straight vertical faces 62. The cutting edges 60 are disposed at an elevation above the ends of the extensions 61 and face inwardly with respect to the strip or ribbon 56 to cut the curved notches 55 therein. The notching punches 57 enter notching dies 63, rigidly held within openings formed in a lower shoe 46, when the upper shoe 48 is moved downwardly toward the lower shoe. The notching dies 63 are cylindrical and have cylindrical bores and the extensions 61 enter these tubular notching dies before the notching edges 60 engage with the strip or ribbon to notch the same.

30 Arranged within the tubular notching dies 63 are plugs 64, which are cylindrically curved, and have their inner portions cut away providing flat faces 65, which afford segmental passages 66 to receive the blanks which are stamped when the
35 notches 55 are produced and these blanks are fed downwardly through the passages. The plugs 64 are provided with reduced cylindrical extensions 67, at their upper ends, which are concentric with the plugs 64 and have their inner faces cut
40 to provide flat faces 68. The flat faces 68 serve as guides for the strip or ribbon. The plugs are held stationary within the notching dies 63. The notching punches 57 may be provided with a stripper 112 and the notching dies 63 with a
45 stripper 88, and these strippers are moved toward the free ends of the elements carrying them, by any suitable means, such as those shown and described in our application Serial No. 317,604.

The operation of the notching means is as follows:

When the shoe 48 is in the uppermost position, the notching punches are elevated sufficiently whereby they disengage the plug extensions 61. The stripper 112 moves outwardly with respect to the notching punches 57 while the stripper

88 moves outwardly with respect to the notching dies 63. The strip or ribbon 56 to be notched passes over the lower stripper 88 and is fed longitudinally in a step-by-step manner, and the length of each step is equal to the distance between the centers of adjacent notches 55. The strip 56 is advanced a step and is brought to rest and during the longitudinal movement of the strip its longitudinal edges contact with the flat faces 68 of the plug extensions 67 and are guided and centered by the plug extensions. The upper shoe 49 is now moved downwardly with respect to the lower shoe 46 and accurately guided in its movement, by any suitable means or by the means shown and described in our copending application 317,604. Before the tubular notching punches 57 enter the tubular notching dies 63, the plug extensions 67 enter the bores 59 of the tubular notching punches, thereby serving to accurately guide the tubular notching punches with respect to the tubular notching dies so that the extensions 61 will first enter the bores of the tubular notching dies 63. The metal strip 56 is held between the strippers 42 and 88 and these strippers move toward the shoes 48 and 46 as the shoe 48 approaches the shoe 46. The extensions 61 enter the bores of the tubular notching dies 63 before the horizontal edges 60 stamp or cut the segmental blanks from the edges of the strip 56. Upon the continued downward movement of the shoe 48 the notching punches move downwardly into the notching dies 63 and the cutting edges cut the segmental blanks from the longitudinal edges of the strip 56 and these segmental blanks are fed downwardly through the segmental passages 66 and are discharged therefrom. After the shoe 48 has been moved downwardly to the lowermost position and a pair of notches 55 stamped the shoe 48 is again shifted to the uppermost position and the cycle of operation is completed.

It is to be understood that the form of our invention herewith shown and described is to be taken as a preferred example of the same and that various changes in the shape, size, and arrangement of parts may be resorted to without departing from the spirit of our invention or the scope of the subjoined claims.

Having thus described our invention, what we claim is:

1. In a machine for notching the edges of a strip to be fed longitudinally, a shoe, transversely spaced tubular notching dies carried by the shoe, a second shoe arranged opposite the first named shoe, tubular notching punches carried by the second shoe and having their inner portions cut away for providing cutting surfaces arranged above the free ends of the tubular notching punches, plugs arranged within the tubular dies and having inner flat faces providing passages within the tubular dies for the blanks stamped from the strip, said plugs having reduced upper extensions having inner flat faces in alignment with the first named inner flat faces, the inner flat faces of the plug extensions contacting with the edges of the strip and serving to guide the strip.

2. In a machine for cutting notches in the edges of a strip, a shoe, tubular notching dies carried by the shoe, a second shoe arranged opposite the first named shoe, tubular notching punches carried by the second named shoe and having their free ends at their inner sides cut

away to provide cutting edges spaced from the free ends of the notching punches, the free ends of the notching punches moving into the ends of the notching dies, plugs arranged within the notching dies and having reduced extensions to enter the tubular notching punches, the plugs being held in place within the notching dies and having their inner faces cut away to provide downwardly discharging passages to receive the blanks cut from the edges of the strip, the inner faces of the plug extensions serving as guide means for the strip.

3. In a machine for cutting notches in the edges of a strip, a lower shoe, a tubular notching die carried by the lower shoe, an upper shoe, a tubular notching punch carried by the upper shoe and having its lower end cut away to provide a cutting edge disposed at an elevation above the lower end of the notching punch, the lower end of the notching punch entering the notching die before the blade stamps out the blank at the edge of the strip, and a plug held within the tubular notching die and having an upper end portion adapted to enter the tubular notching punch, said plug forming with the tubular die a downwardly discharging passage for the blanks stamped from the edge of the strip and the upper end portion serving as a guide for the strip.

4. In a machine for cutting notches in the edge of a strip, a shoe, a tubular notching die carried by the shoe, a second shoe arranged opposite the first named shoe, a tubular notching punch carried by the second shoe and having its free end provided with a cutting edge, the free end of the notching punch moving into the end of the notching die, a plug held within the tubular notching die and forming with the tubular notching die a discharge passage for the blanks, the plug extending beyond the free end of the tubular notching die to enter the tubular notching punch before the tubular notching punch enters the tubular die.

5. In a machine for cutting notches in the edges of a strip, a pair of spaced tubular notching dies, a pair of spaced tubular notching punches having their free ends adapted to be moved into the tubular notching dies, such free ends having cutting edges, plugs held stationary within the tubular notching dies and permanently extending outwardly beyond the free ends of the tubular notching dies to contact with the edges of the strip and guide the same, said tubular notching dies having discharge passages formed between the plugs and the walls of the bores of the tubular dies to receive the blanks.

6. In a machine for cutting notches in the edges of a strip, a pair of spaced tubular notching dies, a pair of spaced tubular notching punches having their free ends adapted to be moved into the tubular notching dies, such free ends having cutting edges, cylindrically curved plugs held within the tubular notching dies and having their inner faces flattened to provide passages within the tubular notching dies, reduced cylindrically curved plug extensions carried by the plugs and arranged in concentric relation thereto and having their inner faces flattened, the inner flat faces of the plug extensions being in alignment with the inner flat faces of the plugs, the plug extensions being adapted to enter the tubular punches.
